(57) **CLAIM**

The ornamental design for a bib, as shown and described.

DESCRIPTION

FIG. 1 is a top perspective view of a bib, showing the first embodiment of my new design; the bib having a narrow perimeter edge;

FIG. 2 is a top plan view of the invention.

FIG. 3 is a bottom plan view of the invention.

FIG. 4 is a left side elevational view of the invention.

FIG. 5 is a right side elevational view of the invention.

FIG. 6 is a rear elevational view of the invention.

FIG. 7 is a front elevational view of the invention.

FIG. 8 is an enlarged, partial, top perspective of the invention showing the perimeter edge.

FIG. 9 is an enlarged partial, top perspective of the invention showing a wide perimeter edge around the lower area of neck opening and narrow edge along the perimeter edge of the neck strap.

FIG. 10 is a top plan of a second embodiment of the bib with a wide perimeter edge; and,

FIG. 11 is a bottom plan view of the invention shown in FIG. 10.

The broken lines represent the portions of the bib, which form no part of the claimed design.
